CURTIS P. BROWN, OF EAST HAMPTON, CONNECTICUT.

SUCTION-ROLLER.

1,145,745.

Specification of Letters Patent.

Patented July 6, 1915.

Application filed April 9, 1914. Serial No. 830,663.

To all whom it may concern:

Be it known that I, CURTIS P. BROWN, a citizen of the United States, and a resident of East Hampton, in the county of Middlesex and State of Connecticut, have invented a new and Improved Suction-Roller, of which the following is a full, clear, and exact description.

My invention relates to suction rollers for extracting moisture from paper or fabrics.

An object thereof is to provide an efficient, simple, and inexpensive roller which requires little power for rotation.

Another object of the invention is to provide a suction roller having a suction chamber of small capacity but of large acting area.

A further object of the invention is to provide a suction roller in which the suction chamber remains substantially invariable, although the rollers forming the chamber vary their relative positions.

A still further object of the invention is to provide a suction roller wherein the sealing rollers forming the suction chamber increase their frictional contact proportionately to the increase of the suction within the chamber.

Another object of the invention is to prevent the sagging of the central portion of the sealing rollers under the action of the atmosphere.

I attain the above objects by the diagrammatic structure illustrated in the accompanying drawings forming a part of the specification, in which similar characters of reference indicate corresponding parts in all the views and wherein—

Figure 1 is a cross section through a suction roller embodying my invention; Fig. 2 is an elevation of the roller partly in section; and Fig. 3 is an end view of the suction roller.

Referring to the drawings, 4 represents a perforated, cylindrical shell the ends of which engage circular recesses 5 of the heads 6, the recess 5 being slightly larger than the exterior diameter of the shell, leaving a lateral displacement to the shell in the heads. Each of the heads 6 is provided with an eccentric hub 7 which forms a bearing for the shaft 8 passing through the heads and shell and the axis of which is parallel to the axis of the shell. A roller 9 is mounted rigidly on the shaft 8 between the heads 6 and,

therefore, the same is placed eccentrically within the shell 4, as best seen in Figs. 1 and 3. The movement from the bearing roller 9 is transmitted to the perforated shell 4 by means of sealing rollers 10 which frictionally engage the shell and bearing roller and are positioned in the narrower part between the shell and roller, so as to form a suction chamber 11 of as small capacity as possible but having a large acting surface. The acting surface is the part of the perforated shell located between the sealing rollers 10, the annular distance between said rollers being preferably from one hundred and thirty degrees to about one hundred and fifty degrees.

I have found by experiment that by placing the sealing rollers in the narrower portion of the eccentric space formed by the shell and bearing roller, as stated, sagging of these rollers under the action of the atmosphere is eliminated. Thus, the length of the suction roller can be greatly increased without any danger of the sealing roller sagging under the pressure when the vacuum in the suction chamber is increased. Sagging of the rollers is not only injurious to the frictional surface of the sealing rollers, but it greatly reduces the vacuum properties of the suction chamber formed by the rollers. Bearings 12 for the rollers 10 are provided in the stationary head which alines the axis of said sealing rollers parallelly to the axis of the shaft 8 and that of the shell 4. The bearings 12, as shown in Fig. 3, leave the axis of the rollers freedom to move in an arc, the center of which is in the axis of the bearing roller; and, therefore, it may be said that the sealing rollers are free to roll within predetermined limits on the bearing roller or are free to float between the shell and bearing roller. It will be also remarked that a displacement of the rollers 10 toward each other will slightly increase the depth of the chamber, that is the distance between the bearing roller 9 and the shell 4; but when the width of the chamber decreases the distance between the sealing rollers will also increase, and, therefore, the capacity of the suction chamber 11 remains substantially unchanged. It will be also noted that the depth of the suction chamber 11 increases from the central part thereof toward the ends, that is, toward the sealing rollers 10. When there is an increase of

atmospheric pressure on the sealing rollers causing them to move toward each other and, therefore, tighten the joint formed by the sealing rollers with the shell and bearing roller, the movement of the sealing rollers 10 within the bearings of the heads 6 necessarily displaces the shell 4; and that is the reason why the said shell has a lateral movement in the circular recess 5 engaging 10 the ends of the shell.

By the eccentric relative position of the shell and bearing roller, I not only prevent the sagging of the sealing rollers under the action of the atmosphere, but I produce a 15 suction chamber of small capacity having a large area of action and which remains substantially invariable during the relative displacement of the rollers forming said chamber.

20 The suction end of the pump is connected to an outlet 14 of the chamber formed in one of the heads 6, while the inlet of the chamber is formed by the apertures in the shell located between the sealing rollers 10. 25 A leather gasket 15 is provided in the recess 5 of the head 6 engaging the ends of the shell and that of the sealing roller and bearing roller, sealing the ends of the chamber 11.

30 From the above it will be seen that I provide a suction roller with an eccentric suction chamber, the sealing rollers of which have a floating movement in the arc, the center of which is in the axis of the bearing roller, and in which roller the relative displacement of the rollers and shell forming 35 the suction chamber leave the suction chamber capacity substantially undisturbed.

Having thus described my invention, I 40 claim as new and desire to secure by Letters Patent:

1. In a suction roller, a perforated cylindrical shell, a bearing roller in the shell eccentric therewith, and sealing rollers engaging 45 the shell and bearing roller and forming therewith a suction chamber, said sealing roller being mounted to float within predetermined limits relatively to the bearing

roller and in an arc the center of which is in the axis of the bearing roller.

2. In a suction roller, a perforated cylindrical shell, a bearing roller in the shell eccentric therewith, sealing rollers engaging the shell and bearing roller and forming therewith a suction chamber, stationary 55 heads engaging the ends of the shell, bearing roller and sealing rollers and sealing the ends of the suction chamber formed by said shell, sealing and bearing rollers, said sealing rollers having their bearings in said 60 heads and mounted to float within predetermined limits between said shell and bearing roller.

3. In a suction roller, a perforated, cylindrical shell, a bearing roller in the shell eccentric therewith, and sealing rollers mounted to float relatively to each other between the shell and the bearing rollers and forming an eccentric suction chamber with 65 said shell and bearing roller.

4. In a suction roller, a perforated, cylindrical shell mounted to float, a bearing roller in the shell eccentric therewith, and sealing rollers between the shell and the bearing forming a suction chamber, said sealing rollers being mounted to move relatively to each other in an arc the center of which is in the 70 axis of the bearing roller.

5. In a suction roller, a perforated, cylindrical shell, a bearing roller in the shell eccentric therewith, and floating sealing rollers between the shell and the bearing rollers forming an eccentric suction chamber, said sealing rollers being in the narrow portion 80 of the eccentric space formed by the shell and bearing rollers and adapted to float relatively to each other and to said bearing roller.

85 In testimony whereof I have signed my name to this specification in the presence of two subscribing witnesses.

CURTIS P. BROWN.
